UNITED STATES PATENT OFFICE.

AVERY E. HOYT, OF CHICAGO, ILLINOIS.

GAS-ENGINE.

1,215,535.

Specification of Letters Patent. Patented Feb. 13, 1917.

Application filed August 18, 1913. Serial No. 735,361.

To all whom it may concern:

Be it known that I, AVERY E. HOYT, a citizen of the United States, residing at Chicago, in the county of Cook and State of Illinois, have invented certain new and useful Improvements in Gas-Engines, of which the following is a specification.

This invention relates to improvements in gas engines, and has for its object to provide a new and improved form of 4 cycle gas engine comprising a cam actuated single sleeve valve construction which gives substantially ideal valve action overcoming valve leakage and loss of power therefrom, and the annoyance of grinding in valves. Another object is to provide a new, simple and improved means for operating the sleeve valve member in such way as to obtain such ideal action.

I am well aware that hitherto gas engines have been constructed embodying slidable sleeve valves adapted to coat with the inlet and outlet ports of the cylinder to control gas admission and exhaust there-through, but so far as I am aware my invention is the first which covers the use of a single sleeve valve, so operated as to give full opening of the inlet port during substantially the entire suction stroke of the piston and a similar full opening of the outlet port during the exhaust stroke of the piston, and complete closure of said ports during both the compression and explosion strokes of the piston, in considering the four stages or strokes of the complete cycle of the ordinary so-called four-cycle engine.

Another object of my invention is to provide an improved form of cylinder and water jacket construction, and a cooling system coating with the same to provide a new and improved system of circulating the cooling fluid about the cylinder walls. Another object is to provide detachable cylinder heads and a new and improved means for cooling and maintaining the same cool.

Still another object of my invention is to provide in a sleeve valve gas engine means to eliminate pressure or suction due to the movement of the sleeve. These and other objects are attained by the construction described and shown in the following specification and accompanying drawings, in which;

Figure 1 is a vertical section along the line 7—7 of Fig. 15 showing the valve mechanism.

Fig. 2 is a detail plan view of the cam, le-

ver sleeve and connection, showing their relative positions.

Fig. 3 is a detail elevation of one of the cams, and showing the approximate amount of travel of same for each of the four stages of the cycle of operations.

Fig. 4 is a detail end elevation of the cam shaft driving means.

Fig. 5 is a side elevation of the same.

Fig. 6 is a diagrammatic view showing the relative positions of the cam, lever, sleeve, piston, crank and connecting rod at the conclusion of the intake stroke and prior to the beginning of the compression stroke.

Fig. 7 is a diagrammatic view similar to Fig. 6 showing the relative positions of the members after approximately $2\frac{1}{2}$ ° further travel of the cam from the position shown in Fig. 6 or 5° travel from the position shown in Fig. 1.

Fig. 8 is a view similar to Figs. 3 and 7 showing the relative position of the members during the compression and explosion strokes.

Fig. 9 is a view similar to Fig. 8 showing the relative position of the members during the exhaust stroke.

Fig. 10 is a cross section on line 3—3 of Fig. 15 between the first and second cylinders, showing the water circulating system.

Fig. 11 is a partial transverse section along the line 4—4 of Figs. 10 and 14.

Fig. 12 is a vertical section of one of the cylinder heads showing water connections thereto.

Fig. 13 is a transverse section of a cylinder of a single cylinder engine showing adaptation of the water cooling system thereto.

Fig. 14 is a side elevation of the cylinders, partially in section, of a four-cycle gas engine showing the water circulating system.

Fig. 15 is a plan view of the same.

Like numerals and letters refer to like elements throughout the drawings, in which 10 indicates in general a four-cycle internal combustion engine comprising a hollow base or main frame 11 to which is bolted a detachable crank case or base 11'. In the main frame 11 is detachably journaled the crank-shaft 12, having crank arm 13, to each of which is pivotally secured a connecting rod 14, pivotally connected at its upper extremity to the wrist-pin 15, in the piston 16, (see Fig. 1). This piston is reciprocably mounted inside the cylinder 17, which is provided

with the inlet and outlet ports 19 and 18 respectively, extending through the cylinder walls.

Slidably mounted in the cylinder is the valve sleeve 20, provided with the relatively offset inlet and outlet ports 21 and 22, located near the upper portion thereof and so relatively spaced that the two ports can not be open at the same time. These ports are of substantially the same size and dimension as those in the cylinder walls and are adapted to coat therewith, as will be hereinafter described. The piston 16 closely fits the inner wall of the sleeve 20 and is adapted 10 to reciprocate therein and relative thereto. The piston 16 is provided with the usual piston rings 16^a coacting with the inner wall of the sleeve 20 to prevent leakage of gas therearound.

Located at the top of the cylinder 17 is the detachable cylinder head 25, provided with the exterior flange 26 adapted to be bolted to the top of the cylinder by studs or bolts 27^a as shown in Fig. 15. This cylinder head 25 projects downwardly into the cylinder 17 and is spaced from the inner wall thereof, leaving the annular chamber or space 27, as shown in Fig. 1 for example.

Carried in annular grooves 25^a of the head 25 are the piston rings 28 of conventional construction. The sleeve 20 is adapted to reciprocate relative to the piston and also the cylinder and moves upwardly and downwardly in the space 27, as will be apparent 35 from an examination of the drawings. The said space 27 is such as to cause a comparatively close fit of the sleeve therein and the rings 28 coat with the inner surface of the sleeve 20 to prevent leakage of the gases 40 into the space 27.

The head 25 is provided with the threaded centrally located aperture 25^b in which may be threaded a spark plug to project partially into the combustion or explosion chamber 45 29. At its lower extremity the sleeve 20 is flared outwardly, as indicated by the numeral 20^a to permit clearance of the connecting rod 14 when in the position shown in Fig. 1. This is to make it possible to drop 50 down the sleeve and thereby shorten the height of the engine.

Projecting outwardly from one side of the flared portion 20^a is the lug 20^b to which is pivotally attached and from which depends the link 30, pivoted at its other extremity to a lever 31. This lever is pivotally fulcrumed at 31^a its outer extremity to the flange 32, projecting inwardly from the portion 33 of the base or main frame 11.

A cam 35 is mounted upon a cam shaft 36 which parallels the crank shaft 12, and is also located in the base or main frame, as shown in Fig. 1. This cam, as viewed in Fig. 3 is provided with the groove 35^a in 65 which is mounted a roller 37 carried by the

lever 31. This roller 37 is mounted upon the pin 37^a secured to the lever 31 by the nut 37^b. The cam groove 35^a is of peculiar configuration, as shown in Fig. 3, in which the cam is viewed from the face or side opposite to that shown in Fig. 1. In engines of more than one cylinder one such cam is provided upon the shaft 36 for each cylinder and is located to coat with a corresponding lever 31 to actuate the corresponding sleeve 20 in 75 the corresponding cylinder.

The driving mechanism to operate the cam shaft, is shown separately for clearness in Fig. 4 and comprises a toothed gear or sprocket 38 which is secured to the crank shaft 12. A second gear or sprocket 39 is similarly secured on the cam shaft 36 in alignment with sprocket 38. A chain 40, which may be of the sprocket or "silent" type extends around and between the sprockets 38 and 39, which are preferably constructed in the ratio of 1 to 2, whereby two rotations of the shaft 12 will cause one rotation of the cam shaft 36. Gears may be substituted for the chain drive if so desired. It 90 will be apparent that each cam 35 makes one complete revolution, while the corresponding piston 16 makes four strokes, two up and two down, which comprise the four stages of a so-called four-cycle motor.

Each of the cams 35 is constructed to operate the corresponding sleeve 20 to obtain the proper regulation of the inlet and outlet ports 18, 19, during the said four strokes of the piston. To obtain this result 100 I have constructed the cam groove 35^a of the configuration shown, so that the cam as it travels from the point *a* to *b* (see Fig. 3) maintains the roller 37 and lever 31 in position shown in Fig. 1, without vertical movement thereof during which time the port 21 in sleeve 20 is held in alignment with the inlet port 19 and the piston traveling on its down stroke draws in the charge of fuel gas.

The travel of the cam from the point *b* to point *c* (see Fig. 6) while corresponding to a very small amount of piston travel, will cause the sleeve to be moved to the position shown in Fig. 6, at which point the port 21 of the sleeve 20 has moved up out of alignment with the intake port 19, and both the ports 19 and 18 are closed, as port 22 in sleeve 20 is still below port 18, and the pressures in ports 18 and 19 and in the cylinder are all balanced, being at atmospheric pressure. Movement of the cam from point *c* to point *d* (see Fig. 7) which is about 5° or less of the cam rotation and consequently only 10° or less of crank travel, will actuate the lever to move the sleeve a considerable distance upward in the cylinder, relatively speaking, during which travel the outlet port 22 of the sleeve 20 will have been quickly carried by the exhaust port 18 in the cylinder. This quick movement takes place pref-

erably during the swing of the corresponding crank and piston rod across dead center, at which time the movement of the piston is practically *nil* and consequently, the charge of gas contained in the cylinder being at approximately atmospheric pressure, there is no discharge of such mixture through the outlet port while the sleeve is making such travel. Further rotation of cam 35 brings the roller 37 to position shown in Fig. 8, raising the sleeve 20 to the highest point, and the sleeve ports above the packing rings, but in no way affecting the ports 18, 19 in the cylinder, the same remaining closed.

15 During the travel of the cam from point *d* to point *e* the roller 37, lever 31 and the sleeve 20 remain stationary. This distance corresponds to substantially two strokes of the piston, namely, the compression and explosion strokes. After reaching the point *e* the roller, actuated by the cam 35, moves the sleeve 20 downwardly so that the openings 18 and 22 align, permitting exhaust of the burned gas from the cylinder. The relative movement of the roller as the cam rotates from point *e* to point *f* causes the movement of the sleeve to such open exhaust position and, as indicated in Fig. 9, corresponds to about 10° or less travel of the cam and consequently 20° or less travel of the crank shaft, the corresponding movement of the piston being slight as the connecting rod is near dead center. This movement of sleeve 20, owing to the construction of the cam, is 25 so rapid as to bring the exhaust ports into quick alignment, the exhaust port beginning to open just at the completion of the down explosion stroke of the piston or practically while the piston rod is swinging across dead center. During the travel of the cam from the position shown in Fig. 9, to the point *g*, the sleeve is held stationary, which is during practically the entire exhaust up-stroke of the piston, maintaining full valve opening 30 for such exhaust.

As the cam rotates from the point *g* to *h* the sleeve is brought quickly into position shown in Fig. 1 and maintained therein during rotation from point *h* to point *c*, the same being the intake stroke of the piston. It will be apparent that by this arrangement of cam, lever and sleeve and the approximate ideal valve action, an exceedingly quick port opening and closing is obtained and the respective ports are maintained in full open position during substantially the entire intake and exhaust strokes of the piston, thus preventing any loss of power by suction or compression of burned gases. Furthermore, it will be apparent that I have provided but a single sleeve to accomplish this valve action, whereas hitherto a plurality of sleeve members or cylinder construction has been employed.

65 To obtain access to the cams, levers and

shafts I provide the cover plate 41 detachably secured by studs or bolts 41^a or the like to the crank case 11. By removal of this plate 41 and disengagement and removal of the levers 31 and bearing caps the entire cam shaft 36 and cams 35 may be readily removed from position, as will be apparent. The bearings 41^b, as shown in Fig. 10, are supported by the partition plates 11^b of the base or crank case 11, the cam shaft 36 being journaled in these bearings 41^b. The crank case bottom 11^a is readily detachable affording easy access to main shaft and connecting rod bearings.

My valve mechanism is adaptable to engines of any number of cylinders. I have shown four cylinders cast *en bloc*, this construction making for efficiency and simplicity. Surrounding and spaced from each of the cylinders 17 are the jackets 50 (see Figs. 85 1 and 11) forming cooling chambers 50^a around the said cylinder walls. These jackets are preferably cast integral in the *en bloc* construction, and the cooling chambers of adjacent cylinders which are separated by thin partitions, formed by the joining of the jackets, are connected through a plurality of passages 51 through said partitions, as shown in Figs. 10, 11 and 14 so that it is apparent water may be circulated 90 from each chamber through the cooling chamber in front thereof to the discharge pipe 65 leading to the radiator. Bosses or projections 52 are provided on the exterior of the jackets 50, in which are the intake 100 and exhaust ports of the cylinder, these bosses or projections being provided with bolt holes 52^a whereby corresponding manifolds may be secured thereto for the admission of gas to and conveying of the 105 burned gases from the cylinders.

A water circulating pump 55 is provided which is driven by a pump shaft 56 operated from the main crank shaft or otherwise. This pump is provided with an intake pipe 57 leading upwardly thereto from the radiator of usual form, but not shown, the pipe 57 being connected thereto in the usual manner. A drain cock 58 is provided in the lowest portion of the pipe 57 to permit draining of the entire water system 115 cylinders and heads, chambers, radiator and pipes.

Leading upwardly from the pump 55 is the water manifold comprising the pipe 59 120 and the two branch pipes 59^a, each of which terminates in a flange 60 secured by bolts or studs 61 to the cylinder jackets between a pair of adjacent cylinders, as shown in Figs. 10, 14 and 15. Each of the branch pipes 59^a is connected with an opening 59^b extending into the cooling chambers of two adjacent cylinders in alignment with the lowest of the passages 51, and so designed as to be tangential to both the cooling chambers. 130

Located in the lowest passage 51 and at the bottom of the cooling chambers opposite the opening 59^a and projecting toward it and integral with the jackets 50 is the wedge shaped partition 62 tapering to an edge opposite the inner end of the opening 59^a. It is apparent that the streams of cooling fluid when injected under pressure through the branches 59^a and openings 59^b into the cooling chambers between the jackets and cylinder walls, are equally divided and diverted by the partitions 62 and caused to circulate all around the base of each of the cylinders equally, thus insuring equal, even and efficient cooling of all the cylinders. As the water is heated it rises to the tops of the cooling chambers by the action of the heat and pump pressure, a thorough spiral agitation being imparted thereto by means of the pump pressure. On reaching the tops of the chambers, it is forced on through the upper openings 51 and the upper parts of intervening chambers and is conducted outwardly through the pipe 63, located at the upper forward point of the cooling chamber of the forward cylinder, and on to the upper portion of the radiator, not shown. It is apparent that this flow of water through the upper parts of the chambers is above the explosion chambers and around the heads and in no way interferes with the cooling of the explosion chamber nor the equal cooling of the heads. It is obvious that I may alter my construction to permit the water to pass out of the top of each cooling chamber into an auxiliary manifold located under manifold 73 or directly into manifold 73 and therethrough to the radiator.

The cylinder heads 25 are provided with the jackets 25^a forming cooling chambers 25^b around the said heads. Leading upwardly to each of the said head cooling chambers is a supply pipe 70 provided with the continuous portion 70^a extending downwardly at one side into the cooling chamber of the corresponding head to the lowest portion thereof. Each of these tubes 70 communicates at its other extremity with the branch pipe 59^a, a pair of these tubes being connected and extending upwardly from each of these branch pipes, as shown in Fig. 14. The tubes or pipes 70 may be formed in sections, as indicated at 71 for ease in assembling and disconnecting, and to permit removal of the heads without disturbing the exhaust manifold.

Connected with and at the top of the cooling chamber of each head, preferably at the side opposite from that at which the pipe 70^a is located, are the outlet pipes 72, each communicating with a discharge manifold 73 of varying diameters to accommodate the increasing volume of water from the rear cylinder to the first. This manifold 73 communicates with the main discharge pipe 65 adjacent the point 74, as shown in Figs. 14 and 15. It is apparent that water forced upwardly through the pipe 70 flows into the corresponding cooling chambers in heads 25, at a point close to the bottom thereof. It then rises by action of the heat and pump pressure to the discharge pipe 72, and from thence is carried out through the manifold 73 and back to the radiator.

When the water in the cooling system is drawn off through cock 58, the lowest point, the cooling fluid in the head chambers 25^b begins to siphon-flow out through pipes 70^a and 70 as soon as the general level falls below the tops of chambers 25^b, and continues so to flow keeping even with the general level, until it reaches the level of the bottoms of chambers 25^b when the heads are fully and automatically drained. The necessary atmospheric pressure to produce this flow is through the feed opening in the radiator.

Inasmuch as the space 27 between the head 25 and cylinder 17 is guarded against leakage therefrom or thereinto, by means of the rings 28, it is apparent that movement of the sleeve up and down therein would compress or rarefy the air therein, causing a loss of power thereby. To obviate this objection I provide what I term inspirator tubes 80 integrally formed in the jackets 50 and, for convenience, preferably located a pair between each two cylinders, as shown in Figs. 10 and 11, for example. These inspirator tubes 80 at their upper end communicate with the upper parts of spaces 27 between the head and cylinder and preferably communicate at their other extremity with the interior of the crank case 11, as shown in Fig. 10. It will be apparent that upward movement of the sleeve will force the air in the space 27 downwardly into the crank case and downward movement of the sleeves will draw air from said crank case into said space 27 and since this air is normally saturated with oil during operation of the motor, a lubricating effect will also be obtained in the said space. I also reserve the right to connect said space 27 with the atmosphere direct by means of an opening through the cylinder walls or the head, not shown. Taking the air from the crank case insures against drawing deleterious dirt into space 27.

In Fig. 13 I have shown a slight modification of the cylinder and jacket construction adapting the circulating system to a single cylinder engine, in which the jacket wall 50' is provided with the tangentially located intake portion 50'', which may be connected to the water supply pipe 59^a, causing the spiral movement to be imparted to the cooling water admitted to the cooling chamber.

The cooling of the head would be effected the same as shown for a multiple cylinder engine.

It is believed that the above description will make clear the operation and construction of my improved engine without the necessity of further explanation.

While I have shown and described my invention with more or less particularity, I do not wish to be restricted to such showing or description beyond the scope of the appended claims.

I claim:-

1. In a device of the class described, a crank case, cylinders mounted upon said crank case, sleeves reciprocably mounted in said cylinders, said sleeves and cylinders being provided with ports therein, pistons reciprocably mounted in said sleeves, a rotatable crank shaft journaled in said crank case, piston rods connecting said crank shaft and pistons, a valve cam shaft below and at one side of said cylinders, a casing for said shaft, said casing being provided with a movable cover plate, bearings carried by said casing, said cam shaft being journaled in said bearings, brackets carried by and projecting into said casing, said brackets being provided with bearings, levers fulcrumed in said bracket bearings, cams carried by said cam shaft, said levers being provided with rollers coating with said

cams, and links connecting said levers with said sleeves whereby the latter may be reciprocated upon rotation of said cam shaft. 35

2. In a device of the class described, cylinders, sleeves reciprocably mounted in said cylinders, said sleeves and cylinders being provided with ports therein, pistons reciprocably mounted in said sleeves, a rotatable crank shaft, piston rods connecting said crank shaft and pistons, a cam shaft at one side of and below said cylinders, cams carried by said shaft, levers having one end fulcrumed, said levers being provided with rollers intermediate their extremities, said cams being grooved, said rollers fitting in said grooves, and links connecting said levers with said sleeves whereby rotation of said cams will operate said sleeves, said grooves in said cams being arranged to maintain said cylinder ports closed during substantially the whole of the compression and explosion strokes of said pistons and to maintain said cylinder ports in open position during substantially the entire exhaust and intake strokes of said piston when said cam shaft is properly rotated. 40 45 50 55

In testimony whereof, I have subscribed my name.
